UNITED STATES PATENT OFFICE.

EDWARD C. JOHNSON, OF KEOKUK, IOWA.

STEAM-PUMP.

SPECIFICATION forming part of Letters Patent No. 502,043, dated July 25, 1893.

Application filed January 16, 1891. Serial No. 377,975. (No model.)

To all whom it may concern:

Be it known that I, EDWARD C. JOHNSON, residing at Keokuk, in the county of Lee and State of Iowa, have invented certain new and useful Improvements in Steam - Pumps, of which the following is a specification, reference being had therein to the accompanying drawings.

This invention relates to steam pumps of the general character known as cycloidal or gyrating pumps.

The object of the invention is to improve the construction of the pumps of the class described, so that the relative pressures of steam and water may be made to conform to the conditions of use; also to generally improve the construction of pumps.

In high service pumps it frequently becomes necessary to work against a pressure of several hundred feet of water, while it may not be convenient or desirable to carry a high steam pressure. Consequently it becomes desirable to balance the steam piston by steam pressure and the water piston by water pressure.

Figure 1 is a vertical section of a steam pump involving the improved construction, the section being taken on the broken line $x-x$, Fig. 5. Fig. 2 is a bottom plan of the central cover of the water piston, showing the springs which rest on the packing. Fig. 3 is a top plan of the pump, with the cover of the water piston removed. Fig. 4 is a side elevation partly sectioned of the water piston cover and packing. Fig. 5 is a plan view of the steam and water cylinders with covers removed, one position of the piston rings being indicated in dotted lines. Fig. 6 is a side elevation of the steam piston, and a broken section of the cover thereof, showing link guide for piston. Fig. 7 is a side elevation of water piston.

The numeral 1 indicates the bottom plate of the engine. This may be a disk or other plate with legs 2, 2, or any other suitable supports. The plate 1 is preferably cut away at 3, 3, to give annular packing surfaces or joints, instead of a single surface, thereby lightening the metal and making better joints.

The bottom plate 1 supports the central water cylinder 4. This cylinder has an outer ring 5, an inner concentric ring or hollow hub

6, and a connecting radial partition 7. The chamber 8 between the rings 5 and 6 does not extend to the lower end of the cylinder 4, but 55 a disk or bottom 9 cuts off the lower part of the cylinder, save where openings or ports 10 and 11 are provided through this bottom 9. The ring 5 is made with a broad bearing at 60 top, and is undercut to reduce weight.

Below the bottom 9 but above the plate 1 there are chambers 12 and 13, connecting to the ports 10 and 11. One of these chambers 12 receives a water supply from the supply pipe or passage 15. The other chamber 13 is 65 a basis for connecting the delivery pipe 16, which leads away from the pump. The piston 20 has a flat ring 21 which fits on top of the two rings 5 and 6, and is broad enough to cover the space between said rings, when shifted from side to side, as about to be described.

A broken ring flange 22 projects from the flat face of ring 21, and extends down into the chamber 8, so that the lower edge of the 75 ring rests on the floor 9, while the ring 21 rests on the top of the cylinder rings 5 and 6, the break in the flange 22 straddling the annular partition 7. The broken ring or flange 22 is of such diameter, (as shown in dotted 80 lines, Fig. 5) that the inner side of the flange 22 at one side of the pump will rest against the outside of the hub 6, while the outside of said flange rests against the inner face of ring 5, the relation of the flange 22 thus being 85 eccentric to the rings 5 and 6.

The piston 20 is caused to move in a gyroscopic manner, with relation to the cylinder, by connection to the steam piston, as will be hereinafter described. The flange 22 moves 90 from side to side in chamber 8 and swings something like a pendulum from the partition 7, at the same time advancing and receding along the partition 7. The result of this movement is to produce a suction which draws 95 in water through port 10, and expels it from port 11, with each swing or impulse of the piston. The disk or ring 21 rests on the top of the rings 5 and 6, and flange 22 rests against the bottom 9 of chamber 8, with close 100 joints.

To secure the seating of the piston in the cylinder, a passage 25 from the escape pipe or from chamber 13, extends through the central

hub, and so up through the ring 21 of the piston. A rod 30 is firmly secured in the central hub, and extends up through the cap or cover 31. A disk 32 serves to center the rod 5 in the hub, said disk 32 being perforated for the passage of water. The cap or cover 31 is a little less in diameter than the ring 21, and a chamber 34 is left between the cap and the ring or plate 21. An annular flange 35, at the 10 edge of cap 31, extends down nearly to the ring 21. Just inside this ring there is a ring packing 36, held down by springs 37, between the packing and cover in addition to the water pressure above said packing. The water 15 from the delivery pipe thus has free entrance to the chamber 34, above the water piston, and bears down on said piston with a pressure proportioned to the area exposed to pressure.

The cover 31 has lugs 39, extending out to 20 the inner edge of the main cover 80, for the purpose of centering and steadyng this cover 31. The chamber 34 may be made of such area as to give the desired excess of pressure on the upper side of the piston ring 21. I 25 proportion the area of the bearing surface for downward pressure in chamber 34, in such manner that any desired overbalance of pressure may be produced to seat the piston. The same is true of the steam piston, to be hereinafter described. The cap 31 is held between a collar 41 on the rod 30, and the nut 33 on said rod. Of course other means for holding the cover or cap might be adopted.

From the above description, it will be seen 30 that the water piston and its cover can be removed from the pump, without disturbing the steam piston.

The upper part of ring 21 is detachable, and under this upper detachable portion there 40 are recesses 44, two, three, or more in number, which receive drivers 45, extending into corresponding recesses in the steam piston ring. The recesses 44 are large enough to permit a slight vertical play, so that the vertical adjustment of the water piston may be quite 45 independent of the steam piston, while the drivers will cause the water piston to oscillate with the steam piston.

The steam cylinder has an annular ring 50 base 50 resting on plate 1, and surrounding the water cylinder. The base 50 has two concentric rings 55 and 56 connected also with rings 5 and 6 and connected by a partition 57, forming a chamber 58, which is annular except for the division by the partition 57. The upper edge of ring 55 is extended outward, and the turned up edge 560 of this outwardly extending rim forms a seat for the annular steam piston cover 80.

60 At the side of the cylinder or casing next to the partition 57 a steam inlet space 59 is formed, and an opening 60 allows steam to enter the annular chamber 58 next to this partition. A corresponding exhaust chamber or space 62 is located at the opposite side of the partition, and steam exhausts into the space and escapes by passages 63. The steam

piston ring 70 rests on top of the rings 55 and 56, and has an annular flange 72 extending down into the chamber 58, and broken to 70 straddle the partition 57. The ring flange 72, indicated in dotted lines, Fig. 5, has the same eccentric relation to the cylinder rings or flanges 55 56 that the water piston has to its ring and hub, and the gyratory movement of 75 the steam piston equals that of the water piston. The ring cap 80 finds its outer bearing 81 on the flange 560 and the inner edge of said cap rests on the piston ring 70, a packing ring 83 being preferably interposed between 80 the cap and the piston, which ring is preferably a compound packing and is surmounted by springs, as has been described for ring 36. This ring cover 80 has a box or recess 90, at the side of the pump which has the partitions. This box 90 is simply an upward extension of the cover to inclose the guiding link 91. The piston ring 70 has an upwardly extending pin 92 above the partition 57, and the link 91 pivots on this pin, and pivots at 90 the other end on a pin 94 which extends down into the box 90. The link 91 being connected to the cover and to the steam piston, prevents the flange 72 of the piston from touching the sides of partition 57. The gyratory movement of the piston is therefore not exactly from the partition, and the reciprocation of the piston is not exactly in a right line, but the slight curve of movement caused by the link is not material.

100 The pin 92 supports a starting rod 95, which has a joint 96 and extends through a stuffing box 97 in the side of box 90, or of the cover 80. The rod 95 may be moved by a lever 98, which has a fulcrum 99, on the casing, and 105 engages a notch 100 in the starting rod. The lever 98 may be moved by hand to throw the steam piston off its dead point, whenever the piston stops on the dead center.

The steam is admitted to chamber 58 close 110 to the partition 57, and produces an oscillatory motion of the flange 72, so as to pass both inside and outside of said flange. The gyratory motion of the steam piston is communicated to the water piston by means of 115 the drivers 45.

The outer edge of rim 21 of the water piston preferably fits close inside the ring 70, but as 120 has been described the water piston can have a slight vertical movement independently of the steam piston.

The water piston cover 31 is preferably strengthened by ribs 300, as indicated in dotted lines, Fig. 2. The ring cover 80 is also strengthened by ribs 800, and held down to the 125 flange 560 of the steam cylinder by bolts and nuts 801.

An oil cup 101 is located in the box 90 above pin 92, and a lubricant from this cup will reach the joints around pin 92, and the 130 lubricant will also pass along a groove 93 in the upper surface of link 91, and thus reach the pin 94.

A drip passage 102 carries off any leakage

or condensation from the annular chamber 103 between the steam cylinder and the water cylinder. The chamber 103 is thus left as an open chamber or air space, and prevents condensation in the steam cylinder by radiation to the water cylinder.

The gyroscopic or oscillating movement of the steam piston in its cylinder is now well understood in this art. This movement of the steam piston is communicated to the water piston, and both pistons swing from the movable center 92, and while the sides of the ring pistons 22 and 72 bear against the rings of the cylinder, the passages alongside the partitions 7 and 57 are always open, as the gap in the ring piston is wider than the thickness of the partitions. A passage 105 leads through the ring of the steam cylinder, so that there is always steam pressure above this piston to balance or overbalance the pressure from below the piston. The location of this passage is not material.

The ability to remove either the steam piston and cap or the water piston and cap without disturbing the remainder of the engine or pump is an important advantage of the construction set forth. The caps and packing determine the downward pressure to seat the pistons, as has been stated.

30 By inclosing the water cylinder and its feed chambers within the steam cylinder, the device is rendered very compact.

The independent vertical adjustment of the two pistons is an important improvement in construction.

35 What I claim is—

1. In a steam pump, the steam cylinder, and water cylinder concentric therewith, and annular steam and water pistons concentric with each other but separably connected, a ring cover for one piston and a cup cover for the other, and a single sliding guide from which the two pistons are guided, all in combination substantially as described.

40 2. The combination with the water cylinder having broken annular chamber as described, of the ring piston having its flange in said chamber, and a cover or cap of less diameter than the ring piston and removably connected to the water cylinder, substantially as described.

45 3. The combination of the water cylinder with annular chamber and central hub, the rod extending up from the hub, the ring piston having its flange in the annular chamber and open around said rod, and a cap or cover held by said rod and having its outer edge bearing by suitable packing on the upper surface of the water piston ring, substantially as described.

50 4. The combination with a base, of the central water cylinder having broken annular chamber with a floor thereto and inlet and outlet ports through said floor but above the base, the water piston in said cylinder, and a removable cap therefor, and a steam cylinder surrounding said water cylinder but of greater

depth, and having a piston and cap separate from the cap of the water cylinder, substantially as described.

5. In a steam pump, a central water cylinder having broken annular chamber and driving piston therein, and a cap over the driving piston, and a steam cylinder having a broken annular steam chamber surrounding the water cylinder and having a driving piston in said chamber and an annular cover therefor, the caps and piston of the steam and water cylinders being separately removable, in combination substantially as described.

6. In a steam pump of the character described, the combination of a central water cylinder having broken annular chamber and piston, a surrounding steam cylinder of similar character and separate piston, and drivers 85 separate from both pistons connecting the two pistons to cause them to partake of the same gyroscopic movement but to permit vertical movement independently of each other, substantially as described.

7. In a steam pump of the character described, the central water piston having recesses in the edges thereof, the surrounding steam piston having similar recesses, and drivers separate from both pistons in said 95 recesses connecting the two pistons but permitting independent vertical movement, and the cylinders and connections, all combined substantially as described.

8. The combination with the central water cylinder, its piston, and a cap for said piston held down by a central rod extending through the piston, of a packing ring interposed between the piston and cap, and springs bearing on the packing ring, all substantially as 105 described.

9. The combination with the divided annular steam cylinder and piston, of a cap above the same having a recess above the break in the piston, a pin extending up from the piston and a link connected to the same and to the cover and serving as a guide for the piston, and a starting bar connected to said guide pin and extending outside the casing, substantially as described.

10. The combination with the divided annular cylinder, piston, and cap, of a guide pin on the piston above the division in the flange thereof, a link connecting said pin to the cap, substantially as described and a starting bar connected to said guide pin and extending outside the casing, substantially as described.

11. The combination with the divided annular steam piston, cylinder, and cap or cover, and pin projecting from the piston opposite the division thereof, of a starting bar connected to said pin and extending outside the casing, and a lever having a bearing on the casing and on the starting bar, substantially as described.

12. The combination with the steam piston, cylinder, casing, and link guide, of a lubricating cup on the casing, and a passage along the link guide from said cup, whereby both

pivots of the link are lubricated from said cup, substantially as described.

13. The combination with the annular water cylinder, and the annular steam cylinder surrounding the same with a chamber between, of an open drip or escape leading from the chamber between the cylinders, substantially as described.

14. The combination with the cylinders, pistons, and annular cap over the steam piston, of the cap over the water cylinder se-

cured to a central support from the hub thereof, said cap having side lugs to bear against and center it in the annular cover to the steam piston.

In testimony whereof I affix my signature in presence of two witnesses.

EDWARD C. JOHNSON.
